UNITED STATES PATENT OFFICE.

JOHN T. LAGOIS, OF BROOKLYN, NEW YORK.

COVER FOR CONTAINERS.

Application filed June 14, 1921. Serial No. 477,463.

To all whom it may concern:

Be it known that I, JOHN T. LAGOIS, a subject of the King of Great Britain, and a resident of the city of New York, borough 5 of Brooklyn, in the county of Kings and State of New York, have invented a new and Improved Cover for Containers, of which the following is a full, clear, and exact description.

10 This invention relates to containers and refers more particularly to an improvement in a cover or movable closure forming a permanent part of the container.

The invention contemplates or comprehends more specifically a simple and inexpensive means for attaching the cover to a container by utilizing the bead employed for connecting the ends and sides of the can together, or the extending or projecting portions of the side walls of the container.

With the above recited and other objects and advantages in view the invention resides in the novel construction, combination 25 and arrangement of parts which will be more fully set forth in the following specification, pointed out in the appended claims and illustrated in the accompanying drawings, it being understood that the right is

30 reserved to embodiments other than those actually illustrated herein, to the full extent indicated by the general meaning of the terms in which the claims are expressed and by variations in the phraseology of

35 the same.

In the drawing—

Figure 1 is an enlarged fragmentary longitudinal sectional view through the upper end of a container equipped with a cover 40 constructed and mounted in accordance with the invention.

Fig. 2 is a transverse sectional view therethrough taken approximately on the line 2—2 of Fig. 1.

45 Fig. 3 is a plan view thereof.

Fig. 4 is a plan view of a modified adaptation of the invention.

Fig. 5 is an enlarged fragmental longitudinal sectional view through the upper 50 end of the container showing modified form of ports in the can end.

Referring to the drawings by characters of reference, a container 10 including side walls 11 and a fixed end 12 is provided, said 55 side walls and end being connected as by a clinched rim or bead 13. The side walls

11 extend slightly beyond the end 12. The end 12 is provided with a plurality of discharge perforations or ports 14 located at one side thereof, which ports may be originally provided during the manufacture of the container or which may be later formed by puncturing weakened portions formed in the same as indicated at 14' in Fig. 5.

A sliding closure member 15 preferably 60 consisting of a sheet of material similar to that of which the container is constructed is provided. The closure member 15 may be formed with upstanding side marginal flanges 16 which are received between the 70 beads 13 of the container whereby to slidably retain the closure member 15 on the container to permit the same to be shifted respectively into positions for covering or uncovering the discharge openings 14, 14'. Preferably the closure member is provided with a manipulating lug 17 which constitutes a manipulative part thereof and is designed normally to lie in the same plane as the remainder of the closure. It will thus 80 be seen that the extending portion of the side wall or walls which as shown are turned slightly inward provides a means for slidably holding the cover against the fixed end 12.

When the consumer purchases the container and desires to discharge the contents therefrom the manipulating lug 17 is bent upwardly at a right angle to the closure 15 as illustrated in Figs. 1 and 3. By using 90 the lug as a manipulating handle, the closure member 15 may be shifted into its respective positions for covering or uncovering the openings 14, 14'. As stated the extending portions of the side walls are bent 95 slightly inward at their upper end to prevent accidental displacement or removal of the closure member, such bending forming a part of the operation in clinching the can and its end 12 together.

In Fig. 4 a modified form of the invention is illustrated in which instance the round container 18 is provided with a circular closure member 19 having an opening 20 therein disposed off center, which opening is designed to register or coincide with an opening 21 of similar configuration provided in the container end when the cover or closure 105 member 19 is rotated. In this instance the closure member 19 is retained in operative position on the container end for example by the clinched bead 22 which secures the end and 110

side of the container together. Although the term end and side walls of the container have been referred to, it is to be understood that the container may be of any dimensions 5 and practically any form and that the end may become the top, bottom or the side wall, or vice versa.

It will thus be seen that a simple and effective means of assembling the closure 10 member with a container is provided which contends to reduce the cost of construction to a minimum, and which eliminates the employment of rivets or other fastening or assembling elements of this character.

Having thus described my invention, what I claim is:

1. In a can, a sheet tin top having edges 15 securely fastened and hermetically sealed to the sides of the can body, said top being scored to outline an aperture without punching the top through so that said top provides a continuous sheet metal end for said can body without apertures punched there-through, a slidable cover piece over said 20 aperture, and means carried by said top for slidably holding said cover piece in place.

2. The combination with a container comprising a body and an end attached thereto by a clinched bead, said end being adapted 25 to provide a discharge opening or ports, of a movable closure member for covering and uncovering said discharge opening or ports comprising a strip of material mounted on said end between opposite portions of the 30 clinched bead and coacting therewith to admit of movement of said strip to covering and uncovering position with respect to the discharge opening or ports.

3. The combination with a container comprising a body and an end attached thereto 35 by a clinched bead, said end being adapted to provide a discharge opening or ports, of a movable closure member for covering and uncovering said discharge opening or ports comprising a strip of material mounted on 40 said end between opposite portions of the

clinched bead and coacting therewith to admit of movement of said strip to covering and uncovering position with respect to the discharge opening or ports, a bendable 50 manipulating extension provided on said strip adapted to normally lie in a plane parallel to the top and capable of bending to an angular position for facilitating the manipulation of the closure member. 55

4. The combination with a container including a body and a top provided with interengageable marginal beads for attaching the same together, said top being adapted to provide a discharge opening or ports, of a 60 closure movably mounted on said top for shifting to positions to respectively close and open the discharge opening or ports, the said bead being bent inwardly to confine the closure member against separation and to 65 permit of shifting movement thereof, as and for the purpose specified.

5. In combination with a container having a fixed end a portion of which is adapted to be perforated, and a side wall extending beyond said end, of a closure slidably held against said end portion by the extending portion of said side wall. 70

6. In combination with a container having a fixed end a portion of which is adapted to be perforated, and a side wall having an inwardly bent portion extending beyond said end, of a closure slidably held against said end portion by the inwardly bent extending portion of said side wall. 75 80

7. In a can, a sheet tin top having inward bent edges hermetically sealed to the sides of the can body and extending upward in protective manner around the edges of the can above the plane of said top, said top being scored to outline an aperture without punching the top through, and a slidable cover piece retained over said aperture by the inward bent portions of said top edges and movable to uncover said aperture portion of said top for opening thereof. 85 90

JOHN T. LAGOIS.
